TYPEWRITING AND LIKE MACHINE

William L. Peters, Mohawk, N. Y., assignor to
Remington Rand, Inc., Buffalo, N. Y., a cor-
poration of Delaware

Application March 28, 1935, Serial No. 13,496

12 Claims. (Cl. 197—63)

My invention relates to typewriting and like machines and particularly to margin stop mechanism. More specifically, my present invention relates to an automatically operated margin stop mechanism and also to the combination of such mechanism with the carriage return mechanism. The main object of my invention, generally stated, is to provide comparatively simple and yet highly efficient means of the character indicated.

10 A further object of my invention is to provide means of the character specified which may be embodied in the nature of an attachment in existing machines without modifying, or materially modifying the structural features thereof.

15 Another object of my invention is to provide an improved automatically operated margin stop which may be controlled from the carriage return mechanism.

20 Still another object of my invention is to provide a selectively controlled and automatically operated margin stop which will be moved to effective position only when the carriage return key is maintained depressed during the entire return movement of the carriage.

25 To the above and other ends which will hereinafter appear my invention consists in the features of construction, arrangements of parts and combinations of devices set forth in the following description and particularly pointed out in the appended claims.

30 In the accompanying drawings wherein like reference characters designate corresponding parts in the different views:

35 Fig. 1 is a fragmentary, front elevational view showing part of a typewriting machine equipped with the devices of my invention;

40 Fig. 2 is a fragmentary, side elevational view of the machine, the view showing particularly the control box and other controlling devices for the carriage return mechanism;

45 Fig. 3 is an enlarged, fragmentary, detail, sectional view taken substantially along the line 3—3 of Fig. 2 and looking in the direction of the arrows at said line;

Fig. 4 is a detail, fragmentary, top plan view of a portion of the machine;

50 Fig. 5 is an enlarged, detail, sectional view taken along the line 5—5 of Fig. 4 and looking in the direction of the arrows at said line;

Fig. 6 is a detail, fragmentary, front elevational view of a portion of the same;

55 Fig. 7 is a disassembled, detail, perspective view of the margin stop of my invention together with

its carrier and a part of its actuating or controlling devices;

Fig. 8 is an enlarged, fragmentary, detail sectional view taken along the line 8—8 of Fig. 2 and looking in the direction of the arrows at said line;

Fig. 9 is a fragmentary, detail, front elevational view, similar to Fig. 6, showing a modified form of part of the actuating or controlling devices for the margin stop of my invention;

Fig. 10 is an enlarged, fragmentary, detail sectional view of the modified construction shown in Fig. 9 and taken along the line 10—10 thereof and looking in the direction of the arrows at said line;

Fig. 11 is a fragmentary, detail, perspective view of a part of the connection for the manual control of the power actuated carriage return mechanism; and

Figs. 12 and 13 are fragmentary face views of two different forms of ledger sheets illustrating one type of office recording in which machines embodying my invention may be used.

I have shown my invention in the present instance embodied in a combined typewriting and computing machine which from certain aspects may be like that disclosed in the application of F. A. Hart Serial No. 510,941, filed January 24, 1931. This machine is known generally as a Remington Electrified Bookkeeping Machine, and is equipped with a power actuated carriage return mechanism of the type shown in the patent to F. A. Hart No. 1,978,997, dated October 30, 1934. In the present instance I have illustrated only so much of the said machine as may be necessary to arrive at an understanding of my invention in its embodiment therein.

While the devices of the present invention may readily be incorporated as an attachment in the machine referred to without modifying, or materially modifying the existing structural features thereof, it should be understood that the invention is not restricted to use in the machine mentioned, but may be employed in typewriting, combined typewriting and computing and like machines generally, wherever found available.

From certain aspects of my invention it may be regarded as an improvement on the construction disclosed in the patent to F. A. Hart No. 1,967,437 dated July 24, 1934. According to the construction disclosed in this patent manually controlled means have been provided that will enable the operator, when desired, to arrest the carriage to the left of the position where ordinarily it is arrested by the operation of the automatically operating carriage return mechanism,

in order that the operator may, at will, begin writing to the left of such ordinary or usual position of arrest. The present invention however, with the above mentioned and other objects in view, aims to provide a selective and automatic control for a margin stop similar to that shown in said Patent No. 1,967,437. With such improvements the new intermediate margin stop adapts itself to wide usage, since an operator is enabled to selectively and automatically control the position to which the carriage will return, the operation of the mechanism being incidental to the actuation of the usual carriage return key, as will hereinafter appear.

15 I shall first describe some of the usual features of construction, including the power actuated carriage return mechanism, with which the devices of my invention are combined, and will then describe such devices. This will be followed by a 20 description of two specific examples of a type of billing and office recording to which the use of the devices of my invention is adapted.

Referring now to the drawings, and particularly Fig. 2, it will be observed that the frame of the 25 machine comprises a two-part base 15, corner posts 16 and a top plate 17. In the present instance the usual carriage of a Remington accounting or typewriting machine, which comprises end bars 18, a rear cross bar 19 and a front cross bar 20, supports a cylindrical platen 21 and is shown mounted to travel over the top plate 17 of the machine from side to side thereof, being propelled in the direction of its feed by the usual spring drum (not shown) under control of the 30 carriage escapement mechanism. Thus, the carriage is mounted in the usual manner to travel on crossed bearing rollers 22 received in oppositely grooved bearings of the rear and front cross bars 19 and 20 respectively, and in fixed rear end 40 front guide bars or rails 23 and 24 respectively.

At any point in the line of travel of the carriage, or automatically at the end of a line, the carriage return mechanism may be actuated to return the carriage to the right in position to begin a new line of writing. The power actuated carriage return mechanism used in the present instance is shown in the above mentioned Hart Patent No. 1,978,997 and will now be briefly described.

50 As shown in Fig. 1, an upright shaft 25, which is preferably mounted on ball bearings, (not shown) is supported from the frame of the machine and has fixedly connected to the upper end thereof a pinion 26. This pinion meshes with a 55 rack bar 21 secured to the carriage. The vertically disposed shaft 25 has a worm wheel 28 loosely mounted thereon and with which a horizontally disposed worm 29 meshes. The worm 29 is fixedly secured to a horizontally disposed 60 driven shaft 30 which may be connected to a main driving shaft 30^a through a clutch 31, said main driving shaft 30^a being constantly rotated by means of a continuously running electric motor (not shown) mounted in the usual manner at the 65 rear of the machine. A second clutch comprising two sections 32 and 32^a is employed to effect an operative connection between the worm wheel 28 and the vertically disposed shaft 25, the section 32^a being splined at 32^b on the shaft 25. 70 Both of the clutches 31 and 32—32^a are controlled by a rock shaft 33 which is connected to said clutches, through clutch controlling arms *a* and *b* respectively in such a manner that when said shaft is rocked in one direction the clutches 75 will be simultaneously released and when the

rock shaft is rocked in the opposite direction said clutches will be simultaneously closed. Thus, it be apparent that when the rock shaft 33 is rocked to close the clutches, the shaft 25 will be rotated and will effect a return of the carriage, 5 as will hereinafter more clearly appear.

I shall now describe the automatically operated means controlled by the travel of the carriage for rocking the main control shaft 33, thus controlling the opening and closing of the clutches 10 by which the motor is rendered effective to return the carriage and is rendered ineffective when the carriage has been returned.

Referring particularly to Figs. 1 and 2 it will be observed that the front cross bar 20 of the carriage carries an adjustable line stop 34. An arm 35 extends into the path of movement of the stop 34 and is carried by a rod 36 supported at one end for limited longitudinal movement in a bearing opening in a bracket 37 secured to the frame of 20 the machine. The left-hand end of the rod 36 is pivotally connected, as at 38, to an upright arm 39 fixed near one end of a short rock shaft 40. To the opposite end of this shaft is fixed a substantially horizontally disposed arm 41, having 25 pivoted thereto a depending rod 42. The lower end of this rod is pivoted at 43 to an angular lever 44, which bears against a stop 44^a when the parts are in normal position shown in Figs. 1 and 2 and is pivotally mounted on a pivot rod 45 30 adjacent a hub or bearing member 45^a pinned or otherwise fixed to said rod. The pivot rod 45 is horizontally disposed and extends across the machine at a point below a control box 46 which is secured to the left-hand side of the machine by 35 means of screws 47 and is the housing for part of the control devices for the carriage return mechanism. An upright arm of the lever 44 is operatively connected to a link or rod 48 by means of a laterally projecting pin 49 provided on said lever and received in an elongated opening 50 in the link 48. The rod 48 carries a hook-like end portion 51 and is guided by a guide member 52 secured to the control box. The hook-like end of the member 48 is adapted to engage behind a pin 45 53 that projects laterally from a holding pawl 54 pivoted at 55 to the control box, said holding pawl being urged in a counter-clockwise direction by a contractile spring 56 which is connected at one end to the pawl 54 and at its opposite end 50 to the link 48. The upper free end portion of the pawl 54 has a hook-like engaging portion 57 adapted to hook over the free end of an arm 58 secured to and projecting forward from the control shaft 33 and urged in a counter-clockwise 55 direction as shown in Fig. 2 by means of a contractile spring 59. Movement of the arm 58 in a counter-clockwise direction tends to turn the shaft 33 in a corresponding direction thereby effecting a closing of the two clutches 31 and 60 32—32^a to render the carriage return mechanism effective. The arm 58, however, is held down in its lower position, where the clutches are maintained released, by the engagement of the pawl 54 with the free end of said arm. When, however, 65 the carriage reaches the end of the line the stop 34 will engage the arm 35 and shift it until it contacts with the bracket 37. The construction of the above described parts is such that when the arm 35 is moved into contact with the bracket 37, 70 the link 48 will be drawn through the intermediate connections to the right as the parts are shown in Fig. 2. This results in moving the pawl 54 out of engagement with the arm 58 so that said arm may be moved upward by the spring 59 75

to effect a closing of both of the clutches and a return of the carriage to the right as hereinbefore described.

This movement of the carriage to the right will continue until a left-hand margin stop 61 contacts with an arm 62 carried by a longitudinally movable rod 63 supported at one end in a bearing opening in the bracket 37. The opposite end of this rod 63 is pivotally connected to an angular lever 64 which is pivoted on the rock shaft 40. The horizontally disposed arm of the angular lever 64 is connected to a depending link 65 the lower end of which is pivoted at 66 to an angular lever 67 pivoted at 68 in the control box 46. The other arm of this angular lever is pivoted at 69 to a longitudinally movable bar 70 supported for sliding movement at its left-hand end, as the parts appear in Fig. 2, by a pin 71 that is received in a slot 72 in said bar. The lower edge of the bar is provided with a cam face 73 that coacts with an anti-friction roller 74 carried by the arm 58. A returning spring 75 encircles the pivot 68 and bears at one end against the side of the control box 46, and at its other end bears against an arm of the angular lever 67 tending to turn said lever in a clockwise direction as shown in Fig. 2.

The effect of moving the rod 63 to the right through the coaction of the margin stop 61 with the arm 62 is to elevate the connecting rod 65 and thus effect a downward longitudinal movement of the bar 70 from the position shown in Fig. 2. This results in bringing the cam 73 into cooperation with the anti-friction roller 74 to thereby depress the arm 58 to a position where the retaining pawl 54 may coact therewith to lock the arm in its depressed position. It will be apparent that this downward movement of the arm 58 to its locked position will effect a clockwise movement of the rock shaft 33 to open the two clutches 31 and 32—32^a and free the carriage from the control of the motor as hereinbefore described.

In addition to the means for automatically returning the carriage in the manner hereinbefore indicated, there is provided the usual carriage return finger key 76 by an actuation of which the carriage may be returned by the motor from any point in the travel of the carriage. As shown in Fig. 11 the key 76 is carried by a lever 77 which is mounted on the rock shaft or pivot rod 45 at the right-hand side of the machine. If desired, a second carriage return key 76^a functioning for the same general purpose as the key 76 may be disposed at the left side of the machine. As shown in Fig. 2, this second carriage return key 76^a is carried by a lever 77^a which is loosely mounted on the bearing member 45^a. A rearwardly extending crank arm 78 is fixed on the inner end of the bearing member 45^a adjacent the lever 77^a and is provided with a laterally projecting pin 79 which coacts with an arm 80 on the lever 44. The construction is such that a depression of the carriage release key 76 will move the lever 44 through the intermediate operative connections in a clockwise direction, as the parts are shown in Fig. 2, thereby releasing the holding pawl 54 and bringing about a closing of the clutches 31, 32—32^a to effect a carriage return in the same manner as the automatically controlled means hereinbefore described.

The manner in which the carriage return key 76^a effects a return of the carriage will be described hereinafter. It will be understood, therefore, that the operator may with the aid of the

release key 76, or 76^a as will hereinafter appear, return the carriage by the power actuated means from any point in the travel of the carriage.

All of the mechanism thus far described, with the exception of the carriage return key 76^a, is 5 of usual construction and is shown in the above mentioned Hart Patent No. 1,978,997. By my present invention I provide auxiliary means in the nature of attachments to function in combination with the features referred to and which 10 auxiliary means will now be described.

Referring particularly to Figs. 1, 4, 5, 6, and 7, it will be seen that a carrier, designated as a whole by the reference numeral 82, is constructed and adjustably mounted in a manner similar to 15 the ordinary margin and line stops 61 and 34 respectively, being provided with locking teeth 83 (Fig. 4) adapted to engage with teeth 84 of a rack bar 85 carried by the front rail 20 of the carriage. The carrier has a cut-out or channelled 20 portion 86 in which a depending flange 87 on a detachable top section 88 of the front carriage bar 20 is received, said top section 88 being positioned above the rack bar 85 and carrying the usual scale 89. At the right-hand end of the 25 channelled portion 86 the width thereof is substantially equal to the thickness of the flange 87, and the rear wall 90 slopes outwardly from this point so that the width of the channel gradually increases toward the left-hand end thereof, as 30 shown in Fig. 4. This construction allows and provides for a fore and aft rocking movement of the carrier around one end thereof on the flange 87 in order to move the teeth 83 out of and into engagement with the rack bar teeth 84. A leaf 35 spring 91 is secured to the carrier at one end in a notch 92 and bears at its free end against the inner face of the flange 90, as shown in Fig. 4. Thus, the center or bowed portion of the spring bears against the rear face of the flange 87 and 40 a force is exerted to swing the carrier 82 rearward with a pivotal movement and maintain the teeth 83 thereon in engagement with the rack bar teeth 84. To release the carrier from the rack bar teeth it is merely necessary to swing the 45 left-hand end thereof forward to disengage the teeth 83 from the rack bar when it may receive a sliding adjustment along the flange 87 to any desired position along the carriage.

As shown in Figs. 4, 6 and 7 the left-hand end 50 of the carrier 82 is provided with a vertically disposed groove or way 94 which is of dove-tail formation in cross section and is adapted to receive a correspondingly shaped intermediate margin stop 95. The margin stop 95 is given 55 a vertical sliding movement in the way 94 into and out of effective position by means of a control lever 96 which is pivoted at 97 on the carrier 82. This lever, in the present instance, is substantially horizontally disposed and is slotted at 60 98 for the reception of a pin 99 carried by the margin stop 95. Fig. 6 shows the stop 95 in its projected or effective position, said stop being limited in its movement to this position by contact of a pin 100 provided on said stop with the 65 lower wall of a notch 101 provided in the carrier 82. Movement of the margin stop 95 to normal position shown in Fig. 1 is limited by contact of a pin 102, provided in the control lever 96 to the right of the pivot 97, with an engaging 70 or stopping edge 103 formed at the right-hand end of the carrier 82. Said stop 95 is resiliently held in this normal position by means of a contractile spring 104 attached at one end to the control lever 96 and at its other end to a pin 105 75

provided in the carrier 82, said spring 104 tending to turn the control lever 96 in a clockwise direction, as the parts are depicted in Fig. 6 for example.

As hereinbefore pointed out, according to my present invention, I have provided means for automatically and selectively moving the margin stop 95 from ineffective to effective position. Such means comprises, in the main, the control lever 96 which is provided with an outwardly bent flange, cam or contact surface 106, and an actuating member or lever 108 mounted on the stationary framework of the machine. When the actuating member 108 is moved to effective position and the carriage is returning to the right the contact surface 106 will come into engagement with said actuating member, and such contact will cause the control lever 96 to turn in a counter-clockwise direction, as shown in Figs. 1 and 6, to move the margin stop 95 to effective position.

I have provided two different forms of mechanisms for controlling the movement of the actuating member 108 to its effective position, one of which constitutes a separate and distinct train of mechanism from said actuating member to the carriage return key 76^a provided at the left-hand side of the machine, while the other train of mechanism includes the usual existing manual controls, including the key 76, for the arm 35 and connected parts. In this last mentioned form of construction the movement of the actuating member 108 is controlled directly from said arm 35. I shall now describe the first form of controlling mechanism for the actuating member 108 in which said member is moved to effective position by a separate and distinct train of connections to the carriage return key 76^a provided at the left-hand side of the machine.

Referring particularly to Figs. 1, 2 and 4, it will be observed that the actuating member 108, in the form of an angular lever, is pivoted at 110 to the stationary framework of the machine, in the present instance to the front guide rail 24 and substantially at the center thereof. Actually the actuating member 108, or the pivot 110 for said lever, is located to the right of the center of the machine a distance substantially the same as the distance between the engaging portion of the margin stop 95 and the left-hand end of the contact surface 106, as those parts are shown in Fig. 6. It will be understood that when the margin stop 95 is in effective position the engaging portion thereof will contact the arm 62 when the carriage is moving to the right to effect an opening of the clutches and stop the carriage. Thus, by mounting the actuating member 108 on the stationary framework of the machine as described above, when it is moved to effective position it will always contact the surface 106 when the carriage is moving to the right no matter where the carrier 82 is mounted or adjusted along the carriage. However, the adjustment of the carrier 82 along the carriage determines the point in the return movement of the carriage where the margin stop 95 will be rendered effective, assuming that the actuating member 108 is in the operative position.

The downwardly extending arm 111 of the angular lever 108 is loosely pivoted at 112 to a link 113 which is adjustably connected by a threaded connection, at 114, to an arm 115 which occupies a position at the front of the machine below the arm 35. A pin 116 connects the arm 115 to a substantially horizontally disposed rod

117 which is supported at the right-hand end thereof, near the connection to the arm 115, in a bearing opening in the bracket 37. The left-hand end of the rod 117 is pivotally connected, as at 118, to an upright arm 119 pivotally mounted on the short rock shaft 40. The short upright arm 119 is one arm of an angular lever, the other substantially horizontally disposed arm 120 of which has pivoted thereto through an elongated pivot or stud 121 a depending rod 122. At its lower end the depending rod 122 is pivoted by means of an elongated pivot or stud 123, as shown in Fig. 3, to a lever 124 which is loosely pivoted on the hub 45^a. As shown in Fig. 2 the lever 124 is angular in shape and at the apex 15 thereof is provided with a hook-like engaging portion 125 which is adapted to engage with a pin 126 provided at the right-hand end of the member 43. Below the pivot 123, the lever 124 is connected to the carriage return lever 77^a by 20 means of a link 127 secured to the levers 124 and 77^a by any suitable means such as the screws 128. Thus, it will be seen that when the carriage return key 76^a is depressed and turns on the hub 45^a, it will, by means of the link 127, effect a 25 downward movement of the rod 122 and a clockwise movement of the lever 124. Such a movement of the lever 124 will effect a release of the arm 58 from the engaging portion 57 of the lever 54 and the carriage will start its return movement to the right. Simultaneously therewith the rod 117 will be moved to the left to cause the angular lever or actuating member 108, to turn in a clockwise direction about its pivot 110 from the position shown in Fig. 1 to that shown in Fig. 6. 35

It will be understood, therefore, that when the key 76^a is depressed, and maintained in depressed position, it will effect a starting of the return movement of the carriage and incidentally will move the actuating member 108 to the position 40 shown in Fig. 6. Thus, with the carriage moving to the right and the actuating member 108 maintained in its vertical position the contact surface 106 of the lever 96 on the margin stop carrier 82 will come into engagement with the actuating member 108 to move the margin stop 95 downward to its effective position. During the return movement of the carriage the margin stop 95 will contact the arm 62 and, due to the movement of the carriage to the right, will move 50 said arm 62 also to the right until stopped by contact with the bracket 37. This will cause a downward longitudinal movement to the right of the member 70 in the control box 46 to effect a downward movement of the arm 58 and a consequent disengagement of the clutches 31 and 32—32^a to stop the action of the carriage return mechanism. In this manner the carriage will be returned and arrested in a position determined by the adjusted position of the margin stop 95 60 and in every instance the clutches will be automatically released and the carriage freed from control of its power actuated return mechanism irrespective of the position to which the margin stop 95 may be adjusted. 65

It will be apparent that while the return key 76^a is held in its depressed position the member 48 will hold the pawl 54 in a released position to the right of that shown in Fig. 2 where it will not be able to engage the free end of the arm 58 70 when said arm is returned through the action of the cam 73 and roller 74 as explained above. Therefore, when the carriage is finally brought to an arrest at the position determined by the automatically operating margin stop 95, the re- 75

turn key 76^a may be released to allow the hook-like engaging portion 57 of the lever 54 to come into engagement with the free end of the arm 58 so that the carriage return mechanism will 5 remain out of operation during the letter space movement of the carriage to the left for another line of work.

Moreover, it will also be apparent that when the member 48 is moved to the right under actuation of the carriage return key 76^a and lever 124, due to the pin and slot connection between the lever 44 and member 48, the train of mechanism between said lever 44 and the arm 35 will be unaffected and is in a condition to be actuated 15 by the line stop 34 when during the next advance movement of the carriage it reaches the end of the line.

I shall now describe the construction and operation of the other or modified form of control mechanism for the actuating member 108, in which the movement of said member to effective position is brought about through the train of mechanism associated with the arm 35. In this modified form of construction all of the parts as 25 described above that are associated with the actuating member 108 to connect it for operation with the carriage return key 76^a have been omitted and yet the same results as described above may be attained. It is obvious, therefore, 30 that the resultant construction is far simpler than that described above and may be regarded as the preferred form of my invention.

In the following description of this simplified and preferred form of my invention the parts 35 which are the same as those described above for the first form of my invention will bear corresponding reference numerals.

Referring particularly to Figs. 9, 10 and 11, it will be observed that an actuating member 40 108^a, which may be the same as the angular lever 108, is pivoted at 110^a to the front guide rail 24 in substantially the same manner and in the same place as the lever 108 described above. The downwardly projecting arm 111^a of the 45 angular lever or actuating member 108^a is pivoted with a loose connection at 112^a to a link 113^a, said link 113^a being in turn adjustably connected, as at 114^a, to a downwardly and forwardly with the aid of the "Skip key tabulator" herein- 50 connected to, or in the present instance formed integral with, an arm 35^a which has the same purpose as the arm 35 described above. The arm 35^a is secured to the rod 36 at the right-hand end thereof and under the influence of said 55 rod 36 or by contact with the line stop 34 may be moved to the left until stopped by engagement with the bracket 37. Due to the addition of the arm 130 to the arm 35^a, it may be found advantageous to provide a guide pin 131 on the 60 arm 130 which may be received in a bearing opening in the bracket 37 to further stabilize and guide the member 35^a in its movement.

It will be recalled that, as described above, when the carriage return key 76 shown in Fig. 65 11 is depressed, the member 78 will be raised to turn the angular lever 44 in a counterclockwise direction. Such movement of the angular lever 44 will effect through intermediate connections a leftward longitudinal movement of the rod 36 70 which will result in drawing the member 35^a—130 to the left and thereby move the actuating member 108^a in a clockwise direction about its pivot 110^a into effective position. Simultaneously with the moving of the actuating member 75 108^a to effective position, the member 48 will

be drawn to the right (in Fig. 2) to bring about a releasing of the clutches and thus start the carriage in its return movement to the right.

Thus, it will be apparent that if the carriage return key 76 is held in its depressed position, 5 the actuating member 108^a will remain in its vertical or effective position so that during the return of the carriage the contact surface 106 will be engaged thereby to move the margin stop 95 into position where the engaging portion 10 thereof will subsequently come into contact with the member 62 to bring about an arrest of the carriage and a freeing of it from control of its power actuated return mechanism. If, however, the carriage return key 76 is not held in 15 its depressed position but is merely given a quick actuation to start the return movement of the carriage, the actuating member 108^a will be ineffective to bring about any movement of the margin stop 95 since said actuating member 108^a 20 will not be retained in a position to contact the surface 106. Therefore, the margin stop 95 will move past the actuating member 108^a and the ordinary margin stop 61 will come in contact with the arm 62 to effect a stopping of the 25 return movement of the carriage in its usual position of arrest and a freeing of it from control of its power actuated return mechanism in the usual manner.

It will be seen that by the present construction of the actuating member 108^a and its manner of connection to the modified arm 35^a—130 I may eliminate the use of a left-hand carriage return key 76^a, lever 124, link 127, rod 122 and the rest of the connections to the link 113 shown 35 in Figs. 1, 2, 4, 5 and 6, as described above. Moreover, as shown in Fig. 11, by eliminating the return key 76^a the pin and slot connection 49—50 between the angular lever 44 and the rod 48 may be omitted. However, if for any reason 40 it is found desirable to have the actuating member 108 or 108^a for the automatically controlled margin stop 95 operated from a separate key, such as the key 76^a, it could be done in the manner described above in accordance with the 45 first form of my invention.

Having thus described the construction and operation of my selectively and automatically controlled intermediate margin stop, I shall now describe two specific types of ledger sheets for 50 use in department store accounting which illustrate certain only of the many applications of a machine embodying my invention.

In Fig. 12 there is shown the usual type of department store ledger sheet in which the amount 51 of the charge for any particular item is inserted on said sheet after the description of the item. The showing in this figure is in the nature of a diagram and is more or less self-explanatory, but I shall nevertheless describe it 6 briefly to point out particularly the role which the devices of my invention play in a set-up of this kind. The machine used for this form of accounting may be a regular No. 85 Remington electrified bookkeeping machine which is equipped with automatic and skip key tabulator mechanism of the type disclosed in the application of Dodge and Philbin filed August 11, 1934, and bearing Serial No. 739,384. The No. 85 Remington electrified bookkeeping machine is also provided with a vertical totalizer for each column in which entries are made and two cross totalizers for totaling and/or proving such entries.

In the drawings and in the following description the amounts are merely for purposes of illustration.

tration. Assuming that the balance to be brought forward is "25 00", this amount is inserted in the proper column as shown in Fig. 12 with both cross and vertical actuators set at disconnect so that said amount will not be entered into any totalizer, or particularly into the totalizer for the "Balance" column. The carriage is then returned to a position for starting a line of entries by giving the carriage return key a quick actuation. This will move the carriage to the right until the margin stop 61 contacts the arm 62 to bring the carriage to rest momentarily, when it next will be automatically tabulated by said Dodge and Philbin tabulator to position for the first digit of the "Previous balance", which it has been assumed is "25 00". This amount is printed and at the letter space after the last zero is printed, the carriage is again automatically tabulated into the center of the "Date" column where the date is printed in a single stroke by the usual date printing type bar, and after this printing the carriage is again automatically tabulated to the "Description" column where the description of the merchandise or type of entry, such as "Cash", "Credit" etc., is made. Since the amount of space taken up by this item may vary, the automatic tabulator is not used to move the carriage into the "Charges" column. Thus, said carriage is moved to the "Charges" column by an actuation of the usual palm tabulator key. The operator then enters the amount "2 25" and depresses the carriage return key. If another item is to be entered for this same date, the operator holds the carriage return key depressed to cause the carriage to stop at the intermediate margin stop position in a manner that has been hereinbefore described. In the present instance, the intermediate margin stop is set for the beginning of the "Description" column as indicated in Fig. 12. The rest of the entries to be made are accomplished in the usual manner, and the carriage is moved from column to column in a manner indicated in Fig. 12 by the use of the dotted lines and arrows and the descriptive matter inserted at the bottom of Fig. 12.

If only one entry is to be made under the first date, instead of returning the carriage to the "Description" column, said carriage is tabulated with the aid of the "Skip key tabulator" hereinbefore referred to, to the "Balance" column in the manner indicated after the second entry of "2 30" in Fig. 12. It will be understood that by the use of the automatically controlled intermediate margin stop of my invention it is not necessary to return the carriage to its extreme right-hand position and then subsequently tabulate it to the "Description" column, but the carriage is automatically stopped in its return movement, as explained above, in the proper place for starting the description of the second item. Therefore the work performed on the machine may be effected more rapidly than heretofore, with less labor and effort on the part of the operator and with less wear and tear on the machine.

In Fig. 13 I have shown a different form of ledger sheet for use in the same type of department store accounting, the chief difference from the ledger sheet shown in Fig. 12 being that the "Charges" column has been shifted to the left of the "Description" column. In practice it has been found that usually many more purchases than one are made on a single day, and by moving the "Charges" column to this new position the work of making the entries is greatly facil-

tated and the entire billing operation is made faster as will hereinafter appear.

With this new form of ledger sheet, after the "Balance brought forward" has been entered, the carriage is returned with the aid of the carriage return key for the entry of the "Previous balance" and "Date" in the same manner as has been described above in connection with Fig. 12. The carriage is then automatically tabulated to the first digital position of the "Charges" column and the amount "2 25" is entered and the carriage again automatically tabulated to the "Description" column. After inserting the necessary descriptive matter in this column, if another charge is to be made on the same day, the electric carriage return key is depressed, and held depressed, to return the carriage to the position of the intermediate margin stop 95, in a manner as described above. As shown in Fig. 13 the intermediate margin stop is set for the next letter space position after the printing of the "Date", so that upon reaching this point the carriage will be automatically tabulated again into the "Charges" column. It will be apparent that the intermediate margin stop is set in this position so that the cross truck will be picked up by the vertical totalizer for the "Charges" column and will thus carry the cross totalizers into the computing zone.

When the totalizer for the "Charges" column has been carried into the computing zone in this manner, the second entry of "2 30" is made and the carriage is again automatically tabulated to the "Description" column for the entries to be made therein. The rest of the operations are done in the usual manner and as indicated in Fig. 13. As with the form of ledger sheet shown in Fig. 12, the use of the intermediate margin stop in the present instance decreases to a minimum all lost motion in preparing a ledger sheet of this general type.

From the foregoing description it will be apparent that I have provided a comparatively simple and yet highly efficient margin stop which may be selectively and automatically controlled from the carriage return mechanism and will be moved to effective position only when the carriage return key is maintained depressed during the entire return movement of the carriage.

While I have described my invention in the present instance in combination with power actuated carriage return mechanism, it should be understood that from certain aspects of my invention it may be embodied in a machine in which the carriage is returned by hand. For example, by breaking the connection between the key 76^a and the power actuated carriage return mechanism, by the elimination of the angular lever 124, for example, we have a construction in which the intermediate stop control mechanism will properly function on the depression of the key 76^a and the return of the carriage by hand.

Various changes may be made in the construction, and certain features thereof may be employed without others without departing from my invention as it is defined in the accompanying claims.

What I claim as new and desire to secure by Letters Patent is:

1. The combination of a carriage, a margin stop adjustable in the direction of the travel of the carriage to different set positions, and automatically operating means for controlling the movement of said stop into and out of effective

position from any of its adjusted positions, said means comprising a controlling lever acting upon said stop and movable therewith, and an actuating member for actuating said controlling lever during movement of the carriage.

2. The combination of a carriage, carriage returning means, key operated means to start said carriage returning means, a margin stop adjustable in the direction of travel of the carriage to different set positions, means coacting with said margin stop to arrest said carriage and disconnect it from said returning means, and means for controlling the movement of said stop into and out of effective position from any of its adjusted positions, the construction and arrangement of said controlling means being such that said stop will be moved automatically to effective position only when said key is held depressed during the entire return movement of the carriage.
- 10 3. The combination of a carriage, power actuated mechanism for returning said carriage, means for rendering said power actuated returning mechanism effective including a carriage return key, a margin stop adjustable in the direction of the travel of the carriage to different set positions, and automatically operating means for controlling the movement of said stop into and out of effective position from any of its adjusted positions, said last mentioned means including an actuating member which is controlled by said carriage return key.

4. The combination of a carriage, power actuated mechanism for returning said carriage, means for rendering said power actuated returning mechanism effective including a carriage return key, a margin stop adjustable in the direction of the travel of the carriage to different set positions, and automatically operating means for controlling the movement of said stop into and out of effective position from any of its adjusted positions, said last mentioned means comprising a controlling lever acting upon said stop and shiftable therewith in its adjustment to different positions, and an actuating member which may be moved by said carriage return key to a position where it will act upon said controlling lever to move said stop to effective position during a return movement of the carriage.

5. The combination of a frame, a carriage mounted thereon for traveling movement, a margin stop carrier adjustable to different set positions in the direction of travel of the carriage, a margin stop carried thereby and shiftable thereon into and out of effective position, a lever pivoted on said carrier and coacting with said margin stop to control its movement to and from effective position, and an actuating member pivoted on said frame and movable to a position where it will act upon said controlling lever to move said stop to effective position during a return movement of the carriage.

6. The combination of a frame, a carriage mounted thereon for traveling movement, a margin stop carrier mounted on said carriage, a margin stop carried thereby and shiftable thereon into and out of effective position, a control lever pivoted on said carrier and coacting with said stop to resiliently hold it in ineffective position, and an actuating member pivoted on said frame and movable to a position where it will act upon said controlling lever to move said stop to effective position during a return movement of the carriage.

7. The combination of a frame, a carriage mounted thereon for traveling movement, a mar-

gin stop carrier mounted on said carriage, a margin stop carried thereby and shiftable thereon into and out of effective position, a control lever pivoted on said carrier and engaging said stop at one end and having a contact surface at the other end, and an actuating member pivoted on said frame and movable to a position where it will engage said contact surface during a return movement of the carriage and thereby turn said control lever about its pivot to move said stop into effective position.

8. The combination of a carriage, power actuated carriage returning mechanism including a constantly rotating shaft, a carriage return key, means operated by said key for coupling the carriage with said constantly rotating shaft to return said carriage, means actuated by said carriage for uncoupling said carriage from said constantly rotating shaft, and shiftable and automatically operating means cooperating with said carriage actuated means to uncouple said carriage from said constantly rotating shaft only when said carriage return key is maintained depressed during the return movement of the carriage.

9. The combination of a carriage, power actuated carriage return mechanism, means including a key for returning said carriage from any position in its line of travel by said power actuated carriage return mechanism, a normally ineffective intermediate margin stop, a normally ineffective actuating device which when effective is operative during the return movement of the carriage to automatically render said intermediate margin stop effective, and means under control of said key for rendering said actuating device effective.

10. The combination of a carriage, power actuated carriage return mechanism, a key for rendering said return mechanism effective, a margin stop effective to arrest the carriage at a beginning of a line position, releasing means cooperative with said margin stop to free the carriage from control of said return mechanism when the carriage is about to be arrested at the beginning of a line position, an intermediate margin stop shiftable into and out of effective position and when in effective position operative to arrest the carriage before it reaches the beginning of the line position determined by said first mentioned margin stop and to coact with said releasing means to free the carriage from control of its return mechanism, and means controlled by the depression of said key for bringing about a movement of said intermediate margin stop to effective position, the construction and arrangement of said last mentioned means being such that said intermediate stop will be moved automatically to effective position only when said key is maintained depressed during the entire return movement of the carriage.

11. The combination of a carriage, power actuated carriage return mechanism, including a constantly rotating shaft and a clutch, a key, means operated by said key for closing said clutch and thereby rendering said return mechanism effective at any desired point in the travel of the carriage, a margin stop effective to arrest the carriage at a beginning of a line position, releasing means cooperative with said margin stop to open said clutch and free the carriage from control of said return mechanism when the carriage is about to be arrested at the beginning of a line position, a normally ineffective intermediate margin stop shiftable into and out of effective position and when in effective position operative to

arrest the carriage before it reaches the beginning of the line position determined by said first mentioned margin stop and to coact with said releasing means to open said clutch and free the carriage from control of its return mechanism, means for adjusting said intermediate margin stop to different set positions along the carriage, and means controlled by the depression of said key for bringing about a movement of said intermediate margin stop to effective position during the return of the carriage, the construction and arrangement of said last mentioned means being such that said intermediate stop will be moved automatically to effective position only when said key is held depressed during the entire return movement of the carriage.

12. The combination of a carriage, power actuated carriage return mechanism, a key for rendering said return mechanism effective, a margin stop effective to arrest the carriage at a beginning of a line position, releasing means cooperative with said margin stop to free the carriage from

control of said return mechanism when the carriage is about to be arrested at the beginning of a line position, an intermediate margin stop shiftable into and out of effective position and when in effective position operative to arrest the carriage before it reaches the beginning of the line position determined by said first mentioned margin stop and to coact with said releasing means to free the carriage from control of its return mechanism, a normally ineffective actuating device which when effective brings about a shifting of said intermediate margin stop to effective position during the return of the carriage, and means controlled by the depression of said key for shifting said actuating device to effective position, whereby when said key is held depressed to return the carriage the intermediate margin stop will be automatically shifted to effective position to arrest the carriage before it reaches the beginning of the line position.

WILLIAM L. PETERS.

CERTIFICATE OF CORRECTION.

Patent No. 2,023,543.

December 10, 1935.

WILLIAM L. PETERS.

It is hereby certified that error appears in the printed specification of the above numbered patent requiring correction as follows: Page 2, second, column, line 2, after the word "it" insert will; page 5, first column, line 49, strike out the words and hyphen "with the aid of the "Skip key tabulator" herein—" and insert instead the syllable and words wardly extending arm 130. This arm 130 is; and that the said Letters Patent should be read with these corrections therein that the same may conform to the record of the case in the Patent Office.

Signed and sealed this 17th day of March, A. D. 1936.

Leslie Frazer

(Seal)

Acting Commissioner of Patents.
